CONTROL MEANS FOR MOTOR DRIVEN SKATES

Oren F. Russell, Palmer, Wash.

Application March 19, 1941, Serial No. 384,219

3 Claims. (Cl. 180—77)

The present invention relates to new and useful improvements in motor driven skates and has for its primary object to provide control means for the motor in which said control means embodies levers attached to a belt secured to the waist of a person and providing flexible cables leading from the levers to the several mechanisms of the motor, such as the switch, timer, clutch and gear shift, for controlling the operation of the motor.

A further object is to provide an attachment of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a front elevational view showing the belt and control levers attached thereto,

Figure 2 is a rear elevational view showing the cables leading along the legs of a person to the motors at the rear ends of the skates,

Figure 3 is a vertical sectional view through the housing of the control lever of the timer and clutch devices,

Figure 4 is a front elevational view of the housing for the gear shift control lever,

Figure 5 is a vertical sectional view through the housing for the switch control lever,

Figure 6 is a transverse sectional view taken substantially on a line 6—6 of Figure 5, and

Figure 7 is a vertical sectional view through the housing of the control lever of the gear shift mechanism.

Referring now to the drawings in detail, wherein for the purpose of illustration I have disclosed a preferred form of the invention, the numeral 5 designates a motor driven ice skate, of which one is adapted for attaching to each foot of a wearer and supported on the rear end of each skate is a motor 6, preferably in the form of an internal combustion engine.

Secured around the waist of the wearer is a belt 7 to the front side of which are secured a plurality of vertical tubes designated at 8, 9, 10 and 11, each of the tubes or housings having ears 12 projecting from opposite sides thereof for securing to the belt.

The housing 8 is provided adjacent its upper end with a vertical slot 13 through which a han-

dle or lever 14 projects forwardly of the housing, the inner end of the lever being attached to a head 15 slidably mounted in the housing and to the lower end of which is attached a pair of flexible wires 16 and 17, leading to the switches (not shown) of the respective motors 6.

The housings 9 and 10 are of identical construction and contain the control mechanism shown in detail in Figure 3 of the drawings. 10 Each mechanism includes a gear 18 journaled on a pin 19 extending transversely at an intermediate portion of the housing and at diametrically opposite sides of the gear 18 are racks 20 and 21, the rack 20 being positioned at the front of the housing immediately behind the vertically extending slot 22 formed adjacent the upper end thereof, while the rack 21 is positioned at the rear of the housing, both of the racks being operatively engaged with the gear as shown 15 in Figure 3 of the drawings.

A lever 23 projects from the upper end of the rack 20 outwardly through the slot 22 and a dog 24 is pivoted as at 25 to the upper portion of the rack 20 for engaging the vertically spaced notches 26 formed in the outer surface of the housing adjacent the slot 22. A coil spring 27 positioned under the lever 23 engages the dog 24 for yieldably urging the same in engagement with the notches. To the lower end of the rack 20 is 20 attached a pair of flexible cables 28 and to the lower end of the rack 21 is attached a similar pair of cables 29.

The cables 28 and 29 of the housing 9 extend to the timing mechanism (not shown) of the 25 respective engines 6 whereas the cables of the housing 10 extend to the clutch mechanism (not shown) also forming part of the control mechanism of the engine. It will be apparent that upon the movement of the rack 20 in one direction that the rack 21 will be moved in an opposite direction to thus control the opposite movement of the timer and clutch mechanisms in a manner as will be apparent.

The housing 11 is provided with a vertically 30 extending slot 30 adjacent its upper end through which projects the lever 31 which is formed on a head 32 slidably mounted in the housing. Also projecting outwardly through the slot 30 is a dog 33 which is pivoted as at 34 to the head, the dog 35 being adapted for engaging the vertically spaced notches 35 formed on the outer surface of the housing adjacent the notch. A coil spring 36 is positioned between the lever 31 and the dog 33 to yieldably urge the dog into engaged position.

A pair of flexible cables 37 are attached to the

lower end of the head 32 and extend downwardly through the lower end of the housing for connection with the gear shift mechanism, (not shown) of each of the engines 6.

It will be understood that the switch, timing mechanism, clutch and gear shift mechanisms of the engine 6 are of conventional construction and adapted to be controlled by the flexible cables leading from the respective levers for opening and closing the switch, advancing or retarding the timer, for moving the clutch into and out of engagement and also for shifting the gears into high or low speed. In view of the fact that such mechanisms are well known in the art it is not deemed necessary to include a detailed disclosure of the same in the present application.

The several sets of cables leading from the levers of the control devices may be slidably mounted through guides 38 attached to the pants legs 39 of the wearer at the inner side thereof, as shown in Figure 2 of the drawings.

It is believed the details of construction, advantages and manner of use of the device will be readily understood from the foregoing without further detailed explanation.

What I claim is:

1. A control attachment for motor driven skates comprising a belt adapted for attaching to a person, a tubular housing attached to the belt and having a longitudinal slot therein, a member slidably mounted in the housing, cables attached to the member and extending from one

end of the housing for attaching to a part of the motor, and a manually actuated device attached to the member and projecting from the slot in the housing, said slot and manually operated device retaining the member against removal from the housing.

2. A control attachment for motor driven skates comprising a belt adapted for attaching to a person, a tubular housing attached to the belt, a member slidably mounted in the housing, cables attached to the member and extending from the housing for attaching to a part of the motor, said housing having a slot therein, a manually actuated device attached to the member and projecting outwardly through the slot and means carried by the manually actuated device and engageable with the housing to secure the member in a predetermined position, said slot and manually actuated device retaining the member against removal from the housing.

3. A control attachment for motor driven skates comprising a belt adapted for attaching to a person, a housing attached to the belt, a gear journaled in the housing, a pair of racks at diametrically opposite sides of the gear and engaged therewith for opposite movement of the racks, cables attached to each rack and extending from the housing for attaching to a part of the motor and a manipulating lever attached to one of the racks for oppositely actuating the cables.

OREN F. RUSSELL.
